(57) **CLAIM**

The ornamental design for a plant light, as shown and described.

DESCRIPTION

FIG. 1 is a front, right and top perspective view of a plant light, showing my new design;

FIG. 2 is a rear, left and bottom perspective view thereof;

FIG. 3 is a perspective view of the plant light in a configuration of use;

FIG. 4 is a front view of the plant light shown in FIG. 1

FIG. 5 is a rear view thereof;

FIG. 6 is a left side view thereof;

FIG. 7 is a right side view thereof;

FIG. 8 is a top view thereof;

FIG. 9 is a bottom view thereof; and

FIG. 10 is an enlarged view of the portion marked "10" in FIG. 1;

FIG. 11 is an enlarged view of the portion marked "11" in FIG. 1;

FIG. 12 is an enlarged view of the portion marked "12" in FIG. 1; and,

FIG. 13 is a perspective view of the plant light in a shortened configuration of use.

The broken lines shown in the drawings illustrate portions of the plant light that form no part of the claimed design.

The alternate length broken lines shown in the drawings are for the purpose of illustrating the boundaries of the enlarged portions seen in FIGS. 1, 10, 11, and 12 and form no part of the claimed design

1 Claim, 13 Drawing Sheets
